UNITED STATES PATENT OFFICE

JOSEPH C. COULOMBE, OF KOKOMO, INDIANA

FUEL FEEDING AND CARBURETING SYSTEM

Application filed March 5, 1925. Serial No. 13,226.

The invention herein described relates to a fuel feeding and carbureting apparatus and is particularly directed to an arrangement in which the fuel reservoir is located at a lower level than the carburetor, while the carburetor, through its connections, provides for raising the fuel and producing the properly attenuated mixture for an internal combustion engine. It is of simple and reliable and efficient construction and the system provides against "flooding."

The above statement indicates, in general, the objects of the invention which primarily contemplates a self feeding carburetor which is not reliant upon gravity flow from the supply tank, but which acquires its fuel from a low level supply and retains, ready for immediate vaporization, or for accelerating purposes, a sufficient supply at a level higher than the main fuel tank.

A further object is to accomplish these desirable results with the ordinary sizes of conduits, commonly employed as standards and without incurring any serious variation in mixture, whether the supply tank is filled to its high level, or depleted to its low level.

Referring to the drawings:

Figure 1, is a somewhat diagrammatic view illustrating the arrangement of the system.

Figure 2, is a vertical sectional view through the carbureting mechanism.

Figure 3, is a view in cross section on the line 3—3 of Figure 2.

Figure 4, is a top plan view of the fuel induction tube.

Figure 5, is a detailed view of the metered opening as it may be applied to the exterior of the tank illustrated in Figure 1.

Referring to the drawings, 1 indicates an internal combustion engine 2, a carburetor suitably connected thereto, and 3, a fuel tank which is ordinarily located at a level lower than the carburetor.

Connecting the carburetor and fuel tank, 45 there is a conduit 4, which has a dependent arm 5, reaching nearly to the bottom of the fuel tank.

Preferably within the fuel tank, although it may be located exteriorly thereof, there is 50 a metered opening 6, in the connecting con-

duit 4. This metered opening may be designed to suit the conditions in any particular case, but ordinarily a small opening about the size of a #65 drill, with the standard type of gasoline fuel pipe is adequate.

The conduit 4, is connected to the carburetor body 7, through the usual connection as at 8, and the fuel drawn through said conduit, first enters an accelerating well 9, through a valve opening 10. This valve opening 10, as illustrated, is formed in an adjustable valve seat 11, and controlled by a metering pin 12, connected with an air valve 13.

An ordinary choke valve 14, is employed at the inlet side of the carburetor and a throttle valve 15, is shown at the opposite side of the air valve 13. A venturi restriction 16, is shown between the air valve 13, and throttle 15, and located in the mixing chamber of the carburetor.

17 indicates the fuel induction tube which extends into the accelerating well 9 and is adjustable up and down—that is in the direction of its longitudinal axis. Besides being hollow, this tube has its walls cut away, so as to furnish communication, near one end, between its interior bore and the well, as indicated at 18, Fig. 2, and near its other end between its interior and the restricted portion 16 of the venturi, as indicated at 24. The particular shape of the openings or passages 24 is not very material, as long as they are of a size to permit the desired movement of fuel. In order to adjust the tube 17 in the direction of its length, I prefer to attach a freely rotatable screw-threaded stem 20 to the tend or top plate 21 of the tube as represented in Fig. 2 and cause this stem to engage with a threaded portion of the body of the carburetor. The stem 20 is provided with an exterior enlargement or a finger piece 22 by which it may be turned to permit adjustments, as will be apparent.

The lower end of the fuel induction tube 17 has a tapered slot 18, so that the higher the level of fuel in the accelerating well or chamber, the smaller the opening from exterior to interior of the induction tube, above the fuel level in the well.

It will, of course, be at once apparent that

with the metered opening 6, there is a broken column of fuel passing from the fuel tank to the chamber 9, during the operation of the engine due to air being taken into the conduit 4 by the induced suction effects.

It is, therefore, preferred to have the metered opening 6, within the tank, as it takes over a saturated air along with the fuel. This saturated air, of course, spreads out in the chamber 9, and is drawn through the tapered slot of the induction tube to the mixing chamber.

If the machine to which this system is applied is unduly thrown out of level, as for instance, in running down hill, so that the fuel tank will be relatively higher than the carburetor and the engine is running, there will be a proper flow to the well 9. However, should the engine be stopped, the induced suction would cease and there would be no flow from the fuel tank through the carburetor, as there could be no siphoning effect.

The direct lift for the fuel is from the fuel level of the fuel tank to the metered opening 6, and from this point, there is not a solid column of fuel. No shut off valve is necessary at the carburetor and obviously, as the direct lift is all in the fuel tank, varying grades have no appreciable effect on the mixture proportions.

Of course, the varying level of fuel, in the main fuel tank, will affect the mixture ratio; but very slightly. For instance, with an eight inch tank, there would be but four inches for variation, if the carburetor is adjusted correctly with the tank half filled and the air valve 13, is weighted to give a constant suction of approximately 2" of mercury or 36" of gasoline. With such an adjustment, the variation of level of fuel in the main tank cannot cause a variation of over 10% and this percentage may be reckoned as 10% "rich" with a full tank and 10% "lean" with an empty tank. This, of course, is negligible as affecting the operation of the engine.

No constant level float is required with this system. There can be no flooding and adjustments may be made with great accuracy.

The fuel induction tube 17, and the accelerating well or chamber 9, perform an important function in securing the desired carburation, as well as in drawing the fuel from the low level tank. Of course, the height of the level of fuel in the chamber 9, varies.

First, the saturated air, above the fuel level, is drawn through the induction tube 60 through the portion of the uncovered slot 18, above the fuel level, the fuel level rises and partially closes the slot 18, to such a point that it adjusts itself to the prevailing depression in the mixing chamber. The level 65 will then remain constant until there is a

variation in degree of the depression or suction.

It follows, that the degree of depression or suction in the mixing chamber will vary the degree of uncovered opening of the slot 18, and level of fuel in the chamber 9. The greater the suction, the greater the exposed portion of the slot and the lower the fuel level.

The chamber 9, and slot 18, provide a temporarily rich mixture on a sudden opening of the throttle for accelerating or "quick pickup".

Of course, a certain amount of air, rich with fuel, enters the chamber 9, and passes on to the mixing chamber thru the tube 17, and this will increase with the degree of suction of the engine, inasmuch as the compensating air valve 13, will raise the metering pin 12, as suction increases beyond certain defined limits. In other words, the speed of movement of the broken column of fuel and air between the main fuel tank and carburetor will vary with the engine speeds and the variable suctions and there will always be a proper compensation to maintain the feed and the residue in the well 9, for quick acceleration of the engine.

Of course, if desired, the air valve 13, may be made adjustable by an adjustable tension spring, though it is preferred to use merely a properly weighted valve and secure an adjustment of the fuel inlet valve between the metering pin 12, and the tapered valve seat 11.

In Figure 6, the metered opening *i*, is formed in a T connection *j*, and connects a duct *l*, with a small chamber *m*. The latter is provided with a suitable cap *n*, and a suitable strainer *o*, may be arranged between the cap and the end of the chamber or the chamber itself may have an additional filling of dust collecting material.

The duct *l*, communicates with the fuel line *p*, and with a dependent tube *r*, the latter extending nearly to the bottom of the fuel tank 3.

Of course, the T is secured in any convenient manner to a flange of the tank.

The advantages of arranging the metered air opening for the fuel line, outside the tank, reside in accessibility and the provisions for renewing the strainer parts so that the air is always well filtered before entering the small metered opening.

It precludes the possibility of fouling the tank and its contents with dust, which would be drawn in through the filler cap, in the ordinary tank, where suction is employed for drawing the fuel to the carburetor or other fuel feeding device.

What I claim as my invention and desire to secure by Letters Patent is:

1. In a fuel feeding and carbureting system, a mixing chamber, a fluid supply tank,

an accelerating chamber connected with the mixing chamber, a valve at the entrance to the accelerating chamber, an air valve controlling the same and varying its positions with variations of suction in the mixing chamber, a conduit connecting the accelerating chamber and supply tank and means for causing fuel and air to be delivered by entrainment through the said conduit.

10 2. In a fuel feeding and carbureting system, a mixing chamber, a throttle at one end thereof, a venturi, an air valve automatically operable by the suction induced in the mixing chamber and venturi, an accelerating chamber having an inlet, a valve controlling said inlet and moved by the air valve, means in the line of fuel flow intermediate the accelerating chamber and mixing chamber for providing a variable fluid opening between said chambers dependent upon the height of liquid in the accelerating chamber and a conduit connecting the accelerating chamber and supply tank for delivering a liquid and a fluid thereto.

25 3. In a fuel feeding and carbureting system, a mixing chamber having a venturi, throttle and air inlet valve, the latter varying in its position according to the suction of the mixing chamber, an accelerating chamber connected with the mixing chamber, an adjustable tube connecting said chambers, said tube having a tapered slot extending within the accelerating chamber, a fuel supply tank and a conduit between the supply tank and accelerating chamber, for delivering liquid and a fluid thereto.

40 4. In a fuel feeding and carbureting system, a mixing chamber, a throttle at one end thereof, a venturi, an air valve automatically operable by the suction induced in the mixing chamber and venturi, an accelerating chamber having a fuel inlet, a valve controlling the said inlet and moved by the air valve, means in the line of fuel flow between the accelerating chamber and the mixing chamber for providing a variable fluid opening between the said chambers dependent upon the height of liquid in the accelerating chamber, and a fuel conduit leading to the accelerating chamber.

JOSEPH C. COULOMBE.
